John F. Allen
New Haven, a Rader
Attorney.

UNITED STATES PATENT OFFICE.

JOHN F. ALLEN, OF BROOKLYN, NEW YORK.

RIVETING-MACHINE.

SPECIFICATION forming part of Letters Patent No. 289,369, dated December 4, 1883.

Application filed February 13, 1883. (No model.).

To all whom it may concern:

Be it known that I, JOHN F. ALLEN, a citizen of the United States, and a resident of Brooklyn, in the State of New York, have invented a new and useful Improvement in Riveting-Machines, likewise applicable for punching and shearing metal plates, of which the following is a specification.

This invention is an improvement of the Letters Patent No. 229,795, granted to me on the 13th day of July, 1880; and the object of my invention is to produce a portable machine for riveting, punching, and shearing metal plates, whereby a greater reach can be obtained than is practicable in the above-mentioned invention; and, further, to obtain the action of the dies square to each other, which particular, when the machine is arranged for punching holes, is of the utmost consequence.

In the accompanying drawings, Figure I represents a front view of a riveting-machine embodying my invention. Fig. II is an end view of the same. Fig. III is a front view of a riveting-machine, showing some modifications, and Fig. IV is an end view of the same.

Similar letters represent similar parts in all the figures.

A is a frame made in the shape of the letter C, to the lower branch or arm of which the lower die, D, is attached. The upper branch or arm of said frame is provided with a suitable hub, B, in which a plunger, E, works freely, to the lower part of which the upper die, D', is attached. To the after part of the frame A a cylinder, G, is attached, of the "trunk" pattern, with the usual valve to admit and exhaust the pressure to be employed, for which latter I prefer compressed air, although steam or water may be used for the purpose. The pressure is admitted through the pipe g. The piston-rod P is attached near the line of the piston, inside the trunk, in the usual manner of that style of engines.

R R are two rods turning on fixed centers n n, attached at the sides of the hub B, Figs. I and II, the outer ends of which rods are attached to the cross-pin L, arranged at the end of the piston-rod P.

T is a rod, shorter than the rods R R, the lower end of which is attached to the plunger

E by means of a suitable joint-pin, a, and the upper end of said rod T is connected to the cross-pin L of the piston-rod.

When the machine is in the position represented in Fig. I, and pressure is admitted behind the piston, the pin L will move in the arc of the circle described by the rods R R, as the lower ends of said rods turn on fixed centers n n, and will move, at the end of the stroke of the piston, to the point L'. During this operation, the rod T being attached at its upper end to this cross-pin L, the lower end of said rod T will be moved downward, moving thereby the plunger E downward, and thus force the die D' upon the rivet, to form thus the desired rivet-head by compression. It will be perceived that the levers R and T form an elbow or toggle-joint, producing very great power, and by this arrangement the movement of the plunger and die D' is in a direct line with the axis of the rivet, insuring thereby a concentric head. By this arrangement I obtain depth of throat or reach and width of grip, directness of stroke, insuring symmetry of rivet-heads, very great power to enable perfect riveting to be done in heavy work, and great lightness, to make the machine easily movable, the weight of the complete machine not exceeding nine hundred pounds, while a ten-inch cylinder with sixty pounds of pressure will produce a pressure on the rivets from fifty to sixty tons.

When the machine is to be used for punching or shearing, suitable tools for either of these purposes must be substituted in place of the dies D and D'. The machines are suspended from the fork or rods J, so situated as to balance the same.

What I claim as my invention, and desire to secure by Letters Patent, is—

In a riveting-machine, the combination of the jaw-frame A, pressure-cylinder G, piston-rod P, rods R R and T, of different lengths, with plunger E and dies D' D, all arranged to operate substantially in the manner and for the purpose described.

JOHN F. ALLEN.
